ADJUSTABLE LAMP STAND

Howard F. Reichenbach, Waterbury, Conn., assignor to The Chase Companies, Incorporated, Waterbury, Conn., a corporation of Connecticut

Application December 6, 1935, Serial No. 53,182

10 Claims. (Cl. 240—81)

This invention relates to an improvement in stands, and particularly to so-called "lamp-stands" which are adjustable to vary the direction of the projected light. Such stands are adapted to be placed upon a table or to be hung upon the headboard of a bed, or used in other situations.

One of the objects of the present invention is to provide a superior adjustable lamp-stand combining neat and attractive appearance with low cost for manufacture.

Another object of the present invention is to provide a superior adjustable lamp-stand including a base, an arm slideable with respect to the said base and carrying a lamp, and having a simple and effective construction and arrangement of parts whereby the wiring leading to the lamp is concealed without, however, precluding the convenient adjustment of the lamp.

With the above and other objects in view, as will appear to those skilled in the art from the following, considered in conjunction with the accompanying drawing and appended claims, the present invention includes all features disclosed therein which are novel over the prior art.

In the accompanying drawing:

Fig. 1 is a view in side elevation of an adjustable lamp-stand embodying the present invention;

Fig. 2 is a view thereof in rear elevation;

Fig. 3 is a vertical, central, sectional view taken on the line 3—3 of Fig. 1;

Fig. 4 is a broken detail sectional view taken on any one of the lines 4—4 of Fig. 1; and

Fig. 5 is a broken, vertical, sectional view taken on the line 5—5 of Fig. 2.

The particular adjustable lamp-stand herein chosen for illustration includes an inverted cup-shaped sheet-metal base or mounting-member, generally designated by the numeral 10 and including a top-wall 11 and a downwardly-extending side-flange or skirt 12. The lower edge of the skirt 12 is curled as at 13 to provide a smooth, non-marring surface for resting upon a table or the like.

Mounted upon the base 10 and forming a unit therewith is a cylindrical guide-head 14 reduced in diameter at its lower end to provide a depending, hollow, externally-threaded stem 15 of lesser diameter than the upper main-portion of the guide-head and resulting in the formation of a downwardly-facing stop-shoulder 16, which engages with the upper surface of the top-wall 11 of the base 10 around a central-passage 17 therein through which the stem 15 extends down-

wardly. The stem 15 of the guide-head 14 also extends downwardly through a central-passage 18 formed in a reinforcing-plate 19 located within the base 10 and clamped against the underside of the top-wall 11 thereof by means of a clamping-nut 20 threaded onto the lower end of the stem 15.

The guide-head 14 is formed diametrically with a guide-passage or guide-way 21 which is intersected by the vertical-passage 22 in the stem 15. The guide-passage 21, just referred to, receives a slideable substantially-semicircular curved supporting-arm 23 and is of rectangular form in cross-section and is sized to receive the supporting-arm 23 with an easy sliding fit. The supporting-arm 23 may, if desired, be provided at its lower end with a terminal-knob or stop 24 and at its upper end rigidly carries an electric-lamp socket 25 which may be of any desired form and which carries an electric bulb 26 and a downwardly-opening hemispherical shade 27. The curvature of the shade 27 substantially conforms to the curvature of the curved supporting-arm 23 and attractively complements the same.

The supporting-arm 23 is of U-shaped form in cross-section, providing a channel 28 which opens on the outside of the curve described by the supporting-arm and which receives one or more suitable wires 29 leading at one end to the socket 25 to supply current to the bulb 26. The said wire 29, opposite the socket 25, leads out of the channel 28 in the supporting-arm 23 downwardly through the vertical-passage 22 in the guide-head 14 and thence radially across the space within the inverted cup-shaped base 11 and outwardly through a ferrule 30 mounted in an opening in the flange or skirt 12 of the base 10.

The curved supporting-arm 23 is adapted to slide through the diametrical guide-passage 21 in the guide-head 14 to permit changes in inclination of the shade 27 and bulb 26 and, owing to the fact that the curved channel 28 in the supporting-arm in effect intersects, whatever its position of adjustment, the vertical-passage 22 in the guide-head 14, the change in adjustment before referred to may be made without cramping the wire 29. If the supporting-arm 23 is adjusted in a clockwise direction from the position in which it is shown in Fig. 1, the added length of the wire 29 will pull in through the ferrule 30 and upwardly through the passage 22 in the guide-head 14. When the supporting-arm 23 is moved in the reverse direction (counterclockwise), a less length of wire will be required to reach the socket 25, and after such adjustment,

a slight pull upon the portion of the wire extending outwardly through the ferrule 30 will tauten the same and cause it to lie smoothly and snugly in the channel 28.

5 For the purpose of clamping the supporting-arm 23 in any desired position of adjustment, the guide-head 14 is provided in its upper end with a vertical threaded bore 31 intersecting the diametrical-passage 21 and receiving the threaded shank 32 of a clamping-screw, generally designated by the numeral 33 and bearing against the upper surface of the supporting-arm 23. The said clamping-screw is provided with a knurled or milled head 34 adapted to be conveniently gripped by the fingers.

10 Owing to the polygonal cross-sectional form of the guide-passage 21 through the guide-head 14 and the substantially-corresponding polygonal transverse form of the supporting-arm 23, the said arm is prevented from unduly rocking laterally with respect to the base 10.

15 If desired, the base 10 may be provided with suitable means such as is now generally in use, by means of which the lamp-stand may be hung 20 from the headboard of a bed or from other vertical surfaces.

25 The invention may be carried out in other specific ways than that herein set forth without departing from the spirit and essential characteristics of the invention, and the present embodiment is therefore to be considered in all respects as illustrative and not restrictive, and all changes coming within the meaning and equivalency range of the appended claims are intended 30 to be embraced therein.

35 I claim:

1. An adjustable lamp-stand comprising a base having a guide-way therein and a wire-passage intersecting the said guide-way; and a longitudinally-curved supporting-arm slidable in the guide-way in the said base and having a curved longitudinal wire-channel opening laterally through one of its sides and intersecting the wire-passage in the said base with respect to which it is slidable.

40 2. An adjustable lamp-stand comprising a base having a guide-way therein and a wire-passage substantially-perpendicular to and intersecting the said guide-way; and a longitudinally-curved supporting-arm slidable in the guide-way in the said base and having a curved longitudinal wire-channel opening laterally through one of its sides and intersecting the wire-passage in the said base with respect to which it is slidable.

45 3. An adjustable lamp-stand comprising a base having a guide-way therein and a wire-passage intersecting the said guide-way; and a longitudinally-curved supporting-arm slidable in the guide-way in the said base and of U-shaped form in cross-section and providing a curved longitudinal wire-channel opening laterally through one of its sides and intersecting the wire-passage in the said base with respect to which it is slidable.

50 4. An adjustable lamp-stand comprising a base having a guide-way therein and a wire-passage substantially-perpendicular to and intersecting the said guide-way; and a longitudinally-curved supporting-arm slidable in the guide-way in the

5 said base and of U-shaped form in cross-section and providing a curved longitudinal wire-channel opening laterally through one of its sides and intersecting the wire-passage in the said base with respect to which it is slidable.

55 5. An adjustable lamp-stand comprising a base having a guide-way therein and a wire-passage intersecting the said guide-way; and a longitudinally-curved supporting-arm slidable in the guide-way in the said base and having a curved longitudinal wire-channel opening laterally through the side thereof of the greatest curvature and intersecting the wire-passage in the said base with respect to which it is slidable.

60 6. An adjustable lamp-stand comprising a base having a transversely-polygonal guide-way therein and a wire-passage intersecting the said guide-way; and a transversely-polygonal longitudinally-curved supporting-arm slidable in the guide-way in the said base and having a curved longitudinal wire-channel opening laterally through one of its sides and intersecting the wire-passage in the said base with respect to which it is slidable.

65 7. An adjustable lamp-stand comprising a hollow base having a guide-way therein, a wire-passage also therein and intersecting the said guide-way at one end and leading to the interior of the hollow base; and a longitudinally-curved supporting-arm slidable in the guide-way in the said base and having a curved longitudinal wire-channel opening laterally through one of its sides and intersecting the wire-passage in the said base with respect to which it is slidable.

70 8. An adjustable lamp-stand comprising a hollow base having a guide-way therein, a wire-passage substantially-perpendicular to and intersecting the said guide-way at one end and leading to the interior of the hollow base; and a longitudinally-curved supporting-arm slidable in the guide-way in the said base and having a curved longitudinal wire-channel opening laterally through one of its sides and intersecting the wire-passage in the said base with respect to which it is slidable.

75 9. An adjustable lamp-stand comprising a hollow base having a guide-way therein, a transversely-polygonal wire-passage also therein and intersecting the said guide-way at one end and leading to the interior of the hollow base; and a transversely-polygonal longitudinally-curved supporting-arm slidable in the guide-way in the said base and having a curved longitudinal wire-channel opening laterally through one of its sides and intersecting the wire-passage in the said base with respect to which it is slidable.

80 10. An adjustable lamp-stand comprising a hollow base having a guide-way therein, a transversely-polygonal wire-passage substantially-perpendicular to and intersecting the said guide-way at one end and leading to the interior of the hollow base; and a transversely-polygonal longitudinally-curved supporting-arm slidable in the guide-way in the said base and having a curved longitudinal wire-channel opening laterally through one of its sides and intersecting the wire-passage in the said base with respect to which it is slidable.

HOWARD F. REICHENBACH.
